JOHN L. SOMMER, OF NEWARK, NEW JERSEY.

DESIGN FOR AN ENVELOP-OPENER.

No. 38,192.

Specification for Design.

Patented Aug. 28, 1906.

Application filed May 23, 1906. Serial No. 318,423. Term of patent 14 years.

To all whom it may concern:

Be it known that I, JOHN L. SOMMER, a citizen of the United States, residing in the city of Newark and State of New Jersey, have invented a new, original, and ornamental Design for Envelop-Openers, of which the following is a specification, reference being had to the accompanying drawings, forming part thereof.

Figure 1 is a side view of an envelop-

opener, showing my new design; and Fig. 2 is an edge view of the same.

I claim—

The ornamental design for an envelop-opener, as shown.

JOHN L. SOMMER.
